(57) **CLAIM**

What is claimed is the ornamental design for a milling tool, as shown and described.

DESCRIPTION

FIG. 1 bottom view of the milling tool.

FIG. 2 is right side elevation view of the milling tool of FIG. 1.

FIG. 3 is a front elevation view of the milling tool of FIG. 1.

FIG. 4 is a left side view of the milling tool of FIG. 1.

FIG. 5 is a rear elevation view of the milling tool of FIG. 1.

FIG. 6 is top view of the milling tool of FIG. 1; and, FIG. 7 is left front perspective view of the milling tool of FIG. 1.

1 Claim, 7 Drawing Sheets---
